Attorney

UNITED STATES PATENT OFFICE.

AUSTIN FLEEGER, OF CHICORA, PENNSYLVANIA.

JOINT FOR ELECTRIC CONDUCTORS.

No. 806,789.

Specification of Letters Patent.

Patented Dec. 12, 1905.

Application filed May 8, 1905. Serial No. 258,716.

To all whom it may concern.

Be it known that I, AUSTIN FLEEGER, a citizen of the United States, residing at Chicora, in the county of Butler and State of Pennsylvania, have invented certain new and useful Improvements in Joints for Electric Conductors, of which the following is a specification, reference being had therein to the accompanying drawings.

- 10 This invention relates to joints for electric conductors, and has for its object to provide a simple and inexpensive joint for the meeting ends of such conductors, which joint may be readily and quickly formed or applied at 15 a minimum of expense and which will not only firmly unite and hold said meeting ends, but also improve the conductivity of the joint by avoiding undue resistance and loss of current.
- 20 To these ends my invention consists in certain novel features, which I will now proceed to describe and will then particularly point out in the claims.

In the accompanying drawings, Figure 1 is 25 an elevation of a joint embodying my invention in one form. Fig. 2 is a similar view with the sleeve or ferrule in longitudinal section. Fig. 3 is a view similar to Fig. 2, showing a modified form. Fig. 4 is a similar view 30 of another modification, and Fig. 5 is a similar view of yet another modification.

In the form of my invention shown in Figs. 1 and 2 the two wires to be united are indicated, respectively, by the reference-numerals 35 1 and 2. The extremities of these two wires are intertwined, as indicated at 3, thereby increasing the diameter of the end portion of each wire and at the same time forming two interlocked coils, which will prevent longitudinal motion of the two wires relatively to 40 each other in either direction. It will be observed in this connection that the straight portions of the wires 1 and 2 are in alinement with each other and that the coiling of the 45 end portions of each wire around the straight portion of the other wire may be dispensed with, as shown in the drawings. 4 indicates a sleeve of conducting material sufficiently ductile to permit of its being swaged, preference being given to copper, brass, or some 50 similar metal or alloy. This sleeve has originally the form of a hollow cylinder or tube of equal diameter throughout, such diameter being great enough to permit it to be slipped 55 over the enlarged ends of the wires. Said sleeve will be slipped over one of the wires

before the ends are intercoiled or intertwined, and after said ends have been brought to the desired condition the sleeve is slipped over the joint or enlarged parts, and the ends 60 of said sleeve lying beyond the enlarged parts are reduced in diameter by a swaging process, as indicated at 5, until they tightly grip and firmly hold the straight portions of the wires 1 and 2, lying adjacent to the enlarged portions 65 of said wires. The annular shoulders 6 thus formed at each end of the sleeve in the interior thereof serve as abutments for the enlarged portions of the wires and will absolutely prevent any movement of said wires 70 relatively to each other which will tend to separate them in the direction of their length, thus adapting the joint to successfully resist severe longitudinal strains on the conductor. It will be seen that the entire joint is inclosed 75 by the sleeve in such a way as to protect it from the weather and its deteriorating influences, while the grip of the ends of the sleeve upon the wires is so firm and their contact therewith so intimate that a permanent 80 joint of high conductivity results, effectually avoiding undue resistance and loss of current and at the same time presenting a practically smooth and uniform exterior. At the same time all soldering is done away with. 85 I prefer to interlock, as well as enlarge, the meeting ends of the wires, and the intertwisting of said ends or forming them into interlocked coils, as shown in Fig. 2, is a desirable 90 construction for that end. Other means for interlocking the said ends may be employed, however, and in Fig. 3 I have shown a construction in which the wires (here indicated by the reference-numerals 7 and 8 (are provided at their ends with hooks 9 and 10, 95 which are engaged with each other in the manner shown. In this case the sleeve (indicated by the reference-numeral 11) may be somewhat shorter, its ends 12 being swaged 100 down to grip the wires on each side of the enlarged portions formed by the hooks in the manner already described. It is not essential to my invention in its broadest form, however, that the ends of the wires should be interlocked, as well as enlarged, and under 105 many conditions it is sufficient to merely enlarge the ends of the wires which are included within the body of the sleeve. One form of construction embodying this feature is shown in Fig. 4, in which the wires (here indicated by the numerals 13 and 14) have their ends 110 enlarged by swaging or some similar process,

as indicated at 15. Here again the sleeve (indicated by the numeral 16) may be comparatively short, being swaged down at 17 to firmly grip the wires on each side of the enlargements 15. The internal shoulders 18 in this case prevent longitudinal separation of the wires, while the abutting of their ends against each other prevents relative motion of the wires in the opposite direction. Of course the enlargement of the ends of the wires may be effected in any suitable manner, and in Fig. 5 I have shown a construction in which the wires (here indicated by the numerals 19 and 20) have the terminal enlargements 21 formed by doubling or bending over the extremities. The sleeve construction in this case is identical with what is shown in Fig. 3.

I do not wish to be understood as limiting myself to the precise details of construction hereinbefore described, and shown in the accompanying drawings, as it is obvious that these details may be modified without departing from the principle of my invention.

Having thus fully described my invention, what I claim as new, and desire to secure by Letters Patent, is—

1. A joint for electric conducting-wires, comprising alined wires provided with enlarged terminal portions, and a sleeve of ductile conducting material inclosing said enlarged portions, extending beyond the same, and having its extremities swaged down so as to firmly grip the straight portions of the wires and present continuous internal annu-

lar shoulders forming abutments which resist longitudinal separating movements of said wires, substantially as described.

2. A joint for electric conducting-wires, comprising alined wires provided with enlarged and interlocked terminal portions, and a sleeve of ductile conducting material inclosing said enlarged portions, extending beyond the same, and having its extremities swaged down so as to firmly grip the straight portions of the wires and present continuous internal annular shoulders forming abutments which resist longitudinal separating movements of said wires, substantially as described.

3. A joint for electric conducting-wires, comprising alined wires provided with enlarged and interlocked terminal portions, and a sleeve of ductile conducting material inclosing said enlarged portions, extending beyond the same, and having its extremities swaged down so as to firmly grip the straight portions of the wires and present continuous internal annular shoulders forming abutments which resist longitudinal separating movements of said wires, the ends of said wires being intertwined to form interlocked coils, whereby the enlargement and interlocking of said ends is accomplished, substantially as described.

In testimony whereof I affix my signature in presence of two witnesses.

AUSTIN FLEEGER.
